UNITED STATES PATENT OFFICE

JOHN E. BELL, OF BROOKLYN, NEW YORK; LOLA R. BELL EXECUTRIX OF SAID JOHN E. BELL, DECEASED

HIGH-PRESSURE BOILER

Application filed April 16, 1924. Serial No. 706,851.

The general object of the present invention is to provide improved apparatus for generating and superheating steam. A more specific object of the invention is to provide steam generating and superheating apparatus of relatively small bulk and weight per unit of capacity which will be durable and efficient, and which in particular, will permit of the high temperature of combustion attainable with the use of pre-heated air for supporting combustion supplied in a relatively small excess over that theoretically required for the combustion of the fuel burned without causing unduly rapid deterioration of the furnace chamber walls. My invention comprises some features of construction and arrangement adapted, and in part especially designed, for use in generating and superheating steam at the very high pressures of 1,200 pounds per square inch or so that are now coming into use, but the general features of my invention for the most part are well adapted for use in generating and superheating steam at other pressures, and particularly at ordinary commercial pressures.

The invention is characterized by the provision of what I may call "extended boiler heating surface" which is adapted to absorb a relatively large amount of heat per unit of heating surface area from products of combustion coming into contact with this surface at a relatively high temperature, in conjunction with provisions for absorbing radiant heat in the combustion chamber proper and in the passage connecting the latter to the chamber in which the extended surface is located, so that while gases initially coming into contact with the extended surface are still very hot their temperature nevertheless is below that at which injurious slag deposits from the heating gases will be made on the extended heating surface. The provisions made for absorbing radiant heat in the combustion chamber and passage leading away from the latter may, and ordinarily will comprise steam superheating surface as well as boiler heating surface proper, and this surface screens or is incorporated in the combustion chamber and passage walls and thereby protects the latter against overheating and

against the erosive action of the non-gaseous fuel residue when the fuel burned is powdered coal, for use of which the invention is especially adapted.

The present invention requires a very compact disposition of the required extended boiler heating surface, which can best be formed by parallel closely spaced gilled tubes such as the tubes encased in externally circumferentially corrugated cast iron casings 55 employed in Foster superheaters and economizers. The effective use of these tubes requires a high gas velocity and a direction of gas flow transverse to the length of the tubes, which should be horizontal, so that a considerable portion of the hot gases is caused to flow through the valleys between the tube gills and furnace dust is swept through, and prevented from depositing in the inter-tube space while at the same time necessarily high 60 draft loss is prevented from becoming excessively large. While the invention was primarily devised for evaporating and superheating water, it has certain especial advantages for use in a power plant comprising a 65 mercury boiler. The horizontal arrangement of the extended boiler surface tubes makes it necessary to provide external means for maintaining the desired water circulation through the tubes, particularly as with the high rate 70 of heat absorption a relatively rapid circulation must be maintained. The external circulation producing effect might be obtained by a feed or re-circulation pump, but I prefer to obtain the desired circulation by arranging 75 the steam and water drums associated with the tubes at a level substantially above the latter with connections between the tubes and drums so disposed as to take full advantage of the difference in the density of the water 80 and steam mixture in the tubes and the connections leading from the latter to the drums and the density of the water in the tube connections leading from the drum to the tubes. Preferably the circulation producing effect 85 thus secured is augmented by arranging the connections leading upward from the tubes to the drums in a position in which these connections will rapidly absorb heat and thus 90 further decrease the density of the water and 95 100

steam mixture in this portion of the circulating system. With the preferred type of extended boiler heating surface described, it is essential to cool the gases before coming into contact with this surface below the point at which any appreciable slag deposit will occur in the extended heating surface, as the character and disposition of the surface makes it practically impossible to remove such deposits from any considerable portion of the surface. This gas cooling effect is obtained, as already explained, by the provisions made for absorbing radiant heat in the combustion chamber in which the surface is located. As a further protection against trouble from slagging, I preferably employ tubes at the top of the bank which have the upper surfaces of their casings smooth so that it will be readily possible to remove slag therefrom.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is an elevation in section on the line 1—1 of Fig. 2;

Fig. 2 is a section on the line 2—2 of Fig. 1;

Fig. 2a is a perspective view illustrating a detail of construction employed in the apparatus shown in Figs. 1 and 2;

Fig. 2b is a section on the line 2b—2b of Fig. 2a.

Fig. 3 is a view taken similarly to Fig. 1, illustrating a modified construction;

Fig. 4 is a section on the line 4—4 of Fig. 3;

Fig. 5 is an elevation of one end of a bank of tubes shown in Fig. 3, with parts broken away and in section;

Fig. 6 is a partial section on the line 6—6 of Fig. 5; and

Fig. 7 is a partial plan on the line 7—7 of Fig. 1.

Figs. 1 and 2 of the drawings illustrate a superheater boiler A primarily devised for use in generating and superheating steam at a pressure of 1,200 pounds per square inch or so, with heat derived by the combustion of powdered coal introduced into the combustion chamber B of the boiler furnace through fuel injectors C of known form which discharge the fuel in downwardly directed jets through openings in the roof of top wall of

the combustion chamber. A small portion of the air required for combustion is introduced with the fuel, but the major portion of the air for combustion enters the combustion chamber B through openings A² in the front and side walls of the chamber from horizontal

channels A' which run along the front and sides of the combustion chamber and are open at their ends to the atmosphere, and also receive atmospheric air through ports controlled by shutters A³ which open into the channels A' through the outer walls of the later. The burning gases pass upward out of the chamber B through a neck portion or port B' into a horizontal channel B² from which the heating gases pass downward through a chamber B³ and thence into an economizer from the lower ends of which the heating gases issue through ports I⁴. The heat absorbing apparatus of the superheater boiler as shown in Figs. 1 and 2 comprises a radiant heat superheater E, a radiant heat superheater F, radiant heat absorbing boiler heating surface G, tubular elements H swept by the heating gases passing through the chamber B³ and forming the major portion of the boiler heating surface proper, economizer tubes I and ash cooling or screen tubes D.

The superheater E, which in the particular construction shown is intended for use in reheating the steam passing from one stage to another of a turbine or turbines, is composed of horizontal elements e in the form of flattened tubes which may be made of cast steel and are incorporated in and form a lining for the major portion of the rear wall of the combustion chamber. The tubular elements e are connected at the sides of the boiler to external vertically disposed headers E'. The screen tubes D are shown as hairpin or U tubes arranged in two sets which collectively form a screen extending across the lower portion of the combustion chamber B and serve to cool the non-gaseous residue of the fuel flowing through the screen into the ash hopper A⁴ at the bottom of the combustion chamber. The tubes D in one set are connected at their ends to inlet and outlet headers D' and D² in front of the combustion chamber B, while the other tubes D are connected to similar headers D' and D² located at the rear of the combustion chamber. The two outlet headers D² are connected by corresponding pipes D³ and D⁴ to a corresponding steam and water drum OA preferably at a level below but adjacent the water level in the drums. In normal operation the water level should be maintained at about the level of the line X—X shown in Fig. 1. The lower end of each drum OA is similarly connected by piping D⁵ to the corresponding ends of the two headers D'.

The radiant heat superheater F is incorporated in and forms a lining for the top wall of the heating gas channel B² and is composed of elements similar to those employed in the superheater E. In the construction illustrated, the elements forming the superheater F are connected at their ends by return bends F⁶ into units each of which

comprises five elements through which the steam passes in series. The steam thus passing through each superheater unit is drawn from a corresponding steam and water drum

5 O through a corresponding pipe f and steam passes from each unit through a corresponding outlet pipe f' to the superheater outlet header F'.

A characteristic feature of the invention 10 is the formation of the major portion of the heat absorbing surface of the boiler proper by a closely spaced bank of horizontally disposed elements H each of which comprises a steel tube h (see Figs. 5 and 6) surrounded 15 by tubular externally corrugated cast steel or iron casing sections h' or h², the elements H being thus generally similar in structure to the well known Foster superheater elements. The tubular casing sections h' may be exactly similar in form to 20 those employed in Foster superheater elements, each such casing element being in the form of a cylinder with external circumferentially extending corrugation grooves. Each of the elements H may be provided 25 with casing sections h', but, advantageously, the elements H in the two top rows of such elements are provided with special casing sections h² in lieu of casing sections h'. The 30 casing sections h² (see Figs. 5 and 6) are formed with smooth oppositely inclined upper surface portions h²⁰ into which the corrugation grooves and intervening ribs at the under sides of the casing sections merge, as 35 shown in Figs. 5 and 6. This facilitates the removal of any slag which may accumulate on the elements H at the top of the bank of such elements. The various elements H are connected in groups for series flow 40 through elements located at successively higher levels from the bottom to the top of the bank by return bend end connections J, which are advantageously, though not necessarily similar in construction to one or 45 another of the forms of construction illustrated in my co-pending application Serial No. 702,012, filed March 26, 1924, patented April 23, 1929, Patent Number 1,710,530.

The end walls of the chamber B³ in which 50 the ends of the tubes H are mounted, may be constructed in various ways. A preferred construction of these end walls and a desirable form of end connections J for use in conjunction therewith, is illustrated in Figs. 55 3, 5, and 6, wherein each end connection comprises a return bend in the form of a tube of the same diameter as the tubes h, which is bent into an arc with tangential end portions which are externally bevelled 60 or made conical in form. In the assembled apparatus each of these conical ends J¹⁰ is inserted in the upwardly flared end h⁵ of the corresponding tube H. The flared tube end h⁵ is received in a heavy metal collar 65 h⁸ having its bore tapered to receive the

flared tube end. Each return bend is surrounded adjacent each end by a collar J' formed with an internal groove into which the return bend tube is expanded. Each collar J' and the corresponding collar h⁶ are 70 secured together by bolts J². The tube sheet H⁴, forming a part of each end wall of the chamber B³, is formed with openings H⁶ receiving the collars h⁶ on the ends of the tubular elements. To facilitate the insertion and removal of the elements H, which may be withdrawn for repair or replacement through the rear wall of the chamber B³, the openings H⁵ in the rear wall at least are horizontally elongated, as shown in Fig. 75 5, so that each opening receives the collars h⁶ of two tubular elements H which, when in place, may be spaced apart by removable blocks of cast iron H⁶. This facilitates the removal and insertion of elements normally 80 located in front of one or another of the down-comer pipes heretofore referred to. The tube sheet walls of the chamber B³ are lined with fire bricks, tiles, plastic fire brick or ganister, and the end connections J are 85 advantageously embedded in Sil-o-cel, or the like refractory heat insulating material packed in a casing H' formed by separable metal plates or sections, and surrounding the end connections. This packing not only 90 restricts the loss of heat by external radiation but also assists in minimizing air leakage through the corresponding walls of the chamber B³. The length of the horizontally disposed elements is reduced to a minimum 95 by placing them directly across the gas passage, and advantageously they are supported at their centers as by the interlaced metal bars H¹⁰ which extend between diagonal rows of elements in two transverse sets as 100 shown in Figs. 5 and 6. Each bar H¹⁰ has an enlarged head H¹¹ engaging upper portions of the surfaces of two elements H in the top row of such elements, thereby preventing the spacing bar from slipping down 105 out of place.

Each element H in the bottom row of those elements is connected at the rear end of the boiler by an end connector J to a bent tube K having its yoke portion located within the 110 chamber B³ and having its outer end connected to the header L. The shape and arrangement of the tubes K tend to prevent or minimize troubles due to thermal expansion and contraction. As shown, there are a plurality of these headers L arranged in an end to end series and each connected by tubes K to five elements H in the bottom row of those elements. Each header L is connected by a 115 down-comer pipe M to the lower end of a corresponding steam and water drum O. Each tubular element H in the top row of the bank of those elements has its rear end connected by a corresponding end connector J to the lower end of the inner tube g of a 120 125 130

corresponding element G. As shown in Fig. 2a, each element G comprises a tube g, preferably of the same diameter as the tubes h, which is encased in cast iron or steel blocks 5 g' rectangular in cross section. Some of the blocks g' have transversely extending supports G' secured thereto by means of which the elements G are supported from a supporting metallic framework G⁵. Advantageously and as shown, the elements G are arranged to form a smooth heat absorbing and gas deflecting surface which is inclined from the vertical so that it projects over the chamber B³ from the rear wall of the latter, 10 and forms the rear end of the channel B². The tubes g, which have their lower ends connected through tubular elements H, end connections J and tubes K to the same header L, and steam and water drum O, are connected to the latter at their upper ends 15 through a corresponding horizontal header P which is connected into the steam and water drum adjacent the water level therein.

The economizer I, through which the heating gases pass downward from the chamber B³, comprises horizontally disposed tubes I which may be similar to the elements H in their construction and in the manner in which they are connected by end connectors 20 J. I³ is the outlet from the economizer for the heating gases. The lowest row of economizer elements I are connected to an economizer inlet header I' and the uppermost row of elements are connected to a header I² 25 which is connected by a tube I³ to a horizontal water distributing drum Q. The latter supplies water to each of the drums O and OA through a corresponding supply branch Q', which advantageously, as shown, enters the 30 drum some distance above the lower end of the latter and comprises a downwardly extending portion within the drum which opens to the latter adjacent its lower end. The drums O and OA, which are arranged 35 in a row extending from one side of the boiler to the other, are each of relatively small diameter, and, in consequence, can be made of ample strength to resist the high pressure of 1,200 pounds per square inch or 40 so for which the boiler shown in Figs. 1 and 2 was primarily devised. Each of the drums O and OA is connected to its neighbor by bent tubes O² which open to the drums below the water level therein, and by bent tubes 45 O³ which open to the drums well above the water level therein. These drums form effective pressure and water level equalizing 50 connections.

In the normal intended operation of the 55 boiler shown in Figs. 1 and 2, a very efficient combustion and correspondingly high combustion temperature is obtained by preheating the major portion of the air supplied to support combustion in its passage through 60 the channels A' and ports A², and by restrict-

ing the air thus supplied to an amount but little in excess of that required to support combustion. Notwithstanding the high temperature of combustion, the walls of the combustion chamber are protected against overheating and are cooled to avoid injury by the erosive action of the nongaseous residue or ash content of the fuel burned, by air passing through the channels A' and ports A² and by the heat absorbing effect of the superheater E, screen tubes D and the portion of the superheater F immediately above the combustion chamber. As a result of the heat thus absorbed and the further absorption of heat by the portion of the superheater F not directly above the combustion chamber and the heat absorption by the elements G, the gases entering the chamber B³ are cooled to a point at which they may safely be brought into contact with the elements H.

The close spacing of the elements H and the corrugated external form of the latter insures a very large amount of highly efficient heating surface in a chamber B³ which is relatively small and in which the ratio of the length of the gas path to its mean hydraulic depth is great enough to insure a high coefficient of heat transfer and the desired reduction in temperature of the heating gases before they pass to the economizer. The results thus obtained would not be obtainable with smooth thin walled tubes in place of the tubular elements H. For one thing, it is not possible to get anywhere near as much heating surface in a chamber B³ of given size with smooth tubes as with the elements H, because it is not practically possible to provide end connections for tubes spaced as closely together as the smooth tubes would have to be spaced to give the same amount of heating surface per unit of space occupied which is readily obtainable with the corrugated elements. This results from the fact that in any event, the tubes must be separated from one another sufficiently far to provide space for the end connections by which the tubes are connected together and to make it possible to mount the tubes in the tube sheets or like supports, with provisions for removing the tubes. In this connection, it should be noted that, with a tubular element H, of the form illustrated and the inner pipe h two inches in diameter, each element has about three square feet of external heat absorbing surface per lineal foot of tube length as against less than six-tenths of a square foot per foot of length of a two inch plain tube.

When, as is usual in boilers, it is attempted to increase the length of gas path and the gas velocity through the inter tube space of a bank of water tubes by baffling that space and thereby providing a plurality of passes of the heating gas from the tubes, it is practically impossible to maintain the baffles tight enough to avoid leakage of the gases

through the baffles, which reduces the efficiency and heat absorbing capacity of the tubes. This difficulty is intensified by the fact that it is difficult to prevent the baffles from burning out and that, when the gas velocity is made high enough to make it materially effective in increasing the heat transfer rate, the draft suction must be correspondingly increased, which, of course, increases the tendency to leakage through the baffles.

The relatively large amount of heating surface per unit of length of the elements H, and the fact that this heating surface is highly efficient, tends, of course, to a very rapid rate of heat absorption by the individual elements with a corresponding large amount of steam generation in each element. This requires a relative rapid circulation of water through the elements H. With the elements H horizontally disposed, as shown, the only head for producing a water circulation in the tube bank itself is in the end connections J, in each of which there is a slight vertical rise. Steam bubbles in passing through the end connections tend to establish a water circulation, but the tendency thus created would hardly be sufficient to insure the amount of circulation required. Ample circulation is insured, however, by locating the steam and water drums O well above the uppermost tubes H, and by exposing the suitably elongated portions of the connections between the drums O and the elements H formed by the elements G to a high heating effect by radiant heat absorption as well as contact with heating gases at high temperature. The circulation is augmented by the fact that the tubes g are nearly straight and may well be as large in diameter as the tubes h, thus minimizing frictional resistance in this portion of the circulating system where the absence of undue frictional resistance and ample flow path cross section is especially desirable in order to obtain full advantage of the presence of steam bubbles in the water. The presence of these steam bubbles in the water materially reduces the weight of fluid column in the pipes G as compared with the weight of columns of the same height and cross section in the water space of the drums O and in the down-comer pipes M. The fact that the heating gases enter the bank of heating tubes H at the top of the bank results in the major portion of the steam formation in the upper elements H and in the elements G which are relatively close to the drums O, thus minimizing the frictional resistance of the water circulation.

With the provisions made for abstracting a large portion of the heat from the gases before the latter enter the bank of tube elements H, little, if any trouble will ordinarily be caused either by slag formations on the elements H or by local heating due to the com-

bustion of carbon-monoxide in proximity to the tube elements. With the special construction of the upper row of elements H shown in Figs. 5 and 6, any nongaseous fuel residue which may deposit on the elements H before being cooled below the slagging temperature may readily be removed from time to time. It will be understood that any usual or suitable provisions may be made for blowing soot or other furnace dust off the surfaces of the elements H from time to time if this is necessary or desirable, but, as the specific character of these provisions form no part of the present invention, I have not thought it necessary to illustrate or describe such provisions herein.

It will be apparent to those skilled in the art that the general principles of my invention may be employed in apparatus quite different in form from that illustrated in Figs. 1 and 2, and that many features of the invention may well be employed in boilers in which the steam pressure is no higher than that now commonly employed in ordinary boiler plants, and in Figs. 3 and 4 I have illustrated a boiler specially designed for use with a moderate pressure of say 400 pounds per square inch. In the boiler shown in Figs. 3 and 4 the multiplicity of small steam and water drums O and OA are replaced by a single horizontal steam and water drum OB. Water passes from the drum OB down to the lowermost elements H through one or more down-comers MA and the distributing header LA. The upper ends of each of the various tubes g may be each connected directly into the drum OB adjacent the water level therein. In Figs. 3 and 4 the steam generated in the boiler furnace is superheated in the superheater E. For this purpose, the steam pipe E¹⁰ leading from the top of the drum OB is connected to one header E' of the superheater E, the superheated steam delivery pipe E²⁰ leading away from the other header E'. The superheater F of the construction first described is replaced in Figs. 3 and 4 by boiler heating surface composed of elements GA similar to the elements G first described, each comprising an inner tube g encased in cast iron sectional casing blocks g'. The upper end of the tubes of the elements GA are each directly connected to the drum OB adjacent the water level therein. The lower ends of the tubes g of the elements GA are connected into a common header G¹⁰ which is connected to the under side of the drum OB by a water circulation pipe or down-comer G¹¹ at each end or side of the boiler.

In this arrangement the roof of the conduit B³ and the elements GA are inclined to augment the water circulation through the elements GA and make unnecessary the pump circulation of the water which might otherwise be required in this portion of the water heating apparatus. The two sets of U-shaped

screen tubes D at the bottom of the combustion chamber B of Figs. 1 and 2 are replaced in the construction of Figs. 3 and 4, by two rows of oppositely inclined tubes D⁴ which extend clear across the end of the combustion chamber and are connected to inlet, intermediate, and outlet headers D¹⁰, D¹⁵, and D²⁰. The outlet header D²⁰ is connected to the drum OB at each end adjacent the water level by a corresponding pipe D²¹ and the inlet header D¹⁰ is connected to branches D²² of the down-comer pipe G¹¹.

The omission in Figs. 3 and 4 of the superheater for re-heating the steam between turbine stages is not undesirable even when the steam is generated at very high pressure where provisions are made for bleeding steam from the turbine to heat the boiler feed water in stages.

It will be apparent that with either form of invention illustrated the circulation through the horizontally disposed water tubes may be augmented by the simple expedient of elevating the steam and water drum or drums and thereby increasing the gravity differential due to the greater density of the water in the down-comer connections as compared with the density of the steam and water mixture in the outlet connections from the water tubes to the steam and water drums.

The apparatus disclosed is characterized by the relatively small amount of liquid space required, particularly in the case of the form illustrated in Figs. 1 and 2, and the invention is therefore well adapted for use in a mercury boiler. For such use, the required amount of mercury, which is expensive, may be minimized by inserting cores in the heating elements. The relatively low height of the furnace and boiler characteristic of my invention, particularly in the form shown in Figs. 1 and 2, is also advantageous for use in a mercury boiler over which a mercury turbine may be placed.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. Steam generating apparatus comprising a chamber, a bank of horizontally disposed water tubes located in said chamber, a steam and water space, means connecting said tubes and space in a circulating

system through which water passes downward from said space to tubes at the bottom of said bank, and thence upward through tubes located at successively higher levels, and thence back to said space through vertically disposed tubular elements located in the upper portion of said chamber, and means for passing heating gases into the upper end of said chamber and thence downwardly over the tubes.

2. The apparatus of claim 1 characterized by a plurality of vertical steam and water drums, each enclosing a portion of the boiler steam and water space and each connected in a separate circulating system with a portion only of said tubes.

3. A boiler furnace comprising a steam and water space, a combustion chamber, heating surface screening the walls thereof and receiving heat by radiation from said chamber, a second chamber alongside the combustion chamber, a heating gas conduit connecting said chambers at their upper ends, water tubes in said second chamber, circulating connections between the tubes and space through which water passes from said space to said tubes, and other circulating connections through which water passes from said tubes back to said space, the last mentioned connections including vertically disposed portions heated by the gases passing through said conduit.

4. A boiler furnace comprising a steam and water space, a combustion chamber, heating surface screening the walls thereof and receiving heat by radiation from said chamber, a second chamber alongside the combustion chamber, a heating gas conduit connecting said chambers at their upper ends, water tubes in said second chamber, circulating connections between the tubes and space through which water passes from said space to said tubes, and other circulating connections through which water passes from said tubes back to said space, the last mentioned connections including vertically disposed portions forming a screen for a portion of the wall of said conduit.

5. A boiler furnace comprising a steam and water space, a combustion chamber, heating surface screening the walls thereof and receiving heat by radiation from said chamber, a second chamber alongside the combustion chamber, a heating gas conduit connecting said chambers at their upper ends, water tubes in said second chamber, circulating connections between the tubes and space through which water passes from said space to said tubes, and other circulating connections through which water passes from said tubes back to said space, the last mentioned connections including tubes surrounded by metal casing elements and extending upward along a portion of the wall of said conduit.

6. A bank of horizontally disposed tubes

with the tubes at the top of the bank formed each with a smooth upper surface and a corrugated under surface, and with the remainder of the tubes formed with external circumferentially extending corrugations.

5 7. A high pressure boiler comprising a bank of horizontally disposed water tubes, a series of vertical steam and water drums, and means connecting each drum and a group of 10 said tubes in a circulation circuit comprising vertically disposed tubular heated portions through which the flow is from the tubes into the drum.

8. In a superheater boiler furnace, a combustion chamber, a second chamber alongside the combustion chamber, a conduit of inverted U shape passing heating gases from the top of the combustion chamber into the top of 15 said second chamber, and steam generating and superheating surface screening the walls 20 of the combustion chamber and the top wall of the conduit and the end wall thereof remote from the combustion chamber and disposed in said second chamber to be heated 25 by contact with the heating gases passing through the latter.

9. In a boiler, a chamber traversed by heating gases, a bank of horizontally disposed water tubes therein, a plurality of vertical 30 steam and water drums, and connections between said tubes and drums providing a plurality of water circulating systems, each including a group of tubes and one of said drums and comprising a down-comer from 35 said drum, a header through which said down-comer is connected to a plurality of tubes at the bottom of the bank, a header connected to the drum and to each of a plurality of tubes at the top of the bank and connections 40 between the tubes of the group providing a plurality of flow paths between said headers each including tubes at different levels.

10. In a boiler, a chamber traversed by heating gases, a bank of horizontally disposed water tubes therein, a plurality of vertical 45 steam and water drums, and connections between said tubes and drums providing a plurality of water circulating systems, each including a group of tubes and one of said drums and comprising a down-comer from 50 said drum, a header through which said down-comer is connected to a plurality of tubes at the bottom of the bank, a header connected to the drum, separate connections from 55 the last mentioned header to each of a plurality of tubes at the top of the bank, the last mentioned connections extending upward from the bank through the upper portion of 60 the chamber, and connections between the tubes of the group providing a plurality of flow paths between said headers, each of which includes the tubes of the group at different levels, and means for passing heating gases 65 downward through said chamber.

11. Apparatus for generating and superheating steam at high pressure comprising a combustion chamber and means for supplying powdered fuel and air for its combustion to said chamber, a second chamber, a conduit for passing heating gases from the top of the combustion chamber into the top of said second chamber, a plurality of vertically disposed steam and water drums, steam generating and superheating surface comprising superheating surface screening the side walls of 70 said combustion chamber and the roof of said conduit, screen tubes extending across the lower portion of said combustion chamber, conduits connecting said screen tubes in a circulating system with one of said drums, a bank of horizontally disposed tubes located in 75 said second chamber and swept by the heating gases passing downward therethrough, and conduits connecting the last mentioned tubes in circulating systems with the drums not connected to said screen tubes.

12. Apparatus for generating and superheating steam at high pressure comprising a combustion chamber and means for supplying powdered fuel and air for its combustion to said chamber, a second chamber, a conduit for passing heated gases from the top of the combustion chamber into the top of said second chamber, a plurality of vertically disposed steam and water drums, and steam generating and heating surface comprising a portion 90 screening the side walls of said combustion chamber and the roof of said conduit, screen tubes extending across the lower portion of said combustion chamber, conduits connecting said screen tubes in a circulating system with one of said drums, and a bank of horizontally disposed tubes located in 95 said second chamber and swept by the heating gases passing downward therethrough, and connections between the last mentioned tubes and the drums not connected to said screen tubes forming water circulating systems including said last mentioned tubes and the 100 drums connected thereto.

13. Apparatus for generating and superheating steam at high pressure comprising a combustion chamber and means for supplying powdered fuel and air for its combustion to said chamber, a second chamber, a conduit for passing heated gases from the top of the combustion chamber into the top of said second chamber, a plurality of vertically disposed steam and water drums, steam generating and heating surface comprising superheating surface screening the side walls of 115 said combustion chamber and the roof of said conduit, screen tubes extending across the lower portion of said combustion chamber and conduits connecting said screen tubes in a circulating system with one of said drums, a bank of horizontally disposed tubes located in 120 said second chamber and swept by the heating gases passing downward therethrough, and 125

130

connections between the tubes at the bottom of said bank and the drums not connected to said screen tubes, connections from the tubes at the top of the bank and the last mentioned drums, the last mentioned connections extending for a part of their length upward from the bank in position to absorb heat from the gases passing to said bank, and connections between the tubes located at different levels in the bank.

10 14. Apparatus for generating and superheating steam at high pressure comprising a combustion chamber and means for supplying powdered fuel and air for its combustion to said chamber, a second chamber, a conduit for passing heated gases from the top of the combustion chamber into the top of said second chamber, and steam generating and superheating surface comprising a portion screening the side walls of said combustion chamber, a portion screening the roof of said conduit, a portion screening the end of said conduit remote from the combustion chamber, and a portion distributed in said second chamber to be heated by contact with the gases passing through the latter.

15 15. Apparatus for generating and superheating steam at high pressure comprising a bank of horizontally disposed water tubes, a row of steam and water drums adjacent one end of the bank of tubes, a row of radiant heat superheating elements, all so arranged that the vertical axes of said drums lie in a plane perpendicular to said tubes and superheating elements, means connecting each of said drums in a circulating system with an adjacent group of the tubes in said bank, and means for passing steam from each drum in series through the superheating elements in 20 an adjacent group of such elements.

25 16. Apparatus for generating steam at high pressure comprising a bank of horizontally disposed water tubes, a plurality of vertical steam and water drums, and means for connecting each steam and water drum in a circulating system with a plurality of said tubes, said means comprising upper and lower headers and a connection from each of the drums, and means connecting the tubes of 30 each group between the headers to provide a plurality of flow paths between the latter each comprising a plurality of tubes at different levels through which a series flow occurs.

35 17. In a boiler comprising a bank of horizontally disposed water tubes and a steam and water space to which said tubes are connected by means comprising a row of down-comer pipes extending in front of the bank 40 at one end thereof, removable return bends connecting the ends of adjacent tubes and a tube supporting sheet at the end of the bank adjacent the down-comer pipes formed with horizontally elongated slots each receiving the ends of a plurality of said tubes

whereby the tubes may be laterally disposed with respect to the down-comer pipes if necessary to effect their insertion in and removal from the bank.

Signed at New York city, in the county of 70 New York and State of New York, this 14th day of April, A. D. 1924.

JOHN E. BELL.
